DESIGN FOR A COSMETIC CONTAINER

Albert Weewetzer, Elgin, Ill., assignor to Illinois Watch Case Company, Elgin, Ill., a corporation of Illinois

Application September 11, 1935, Serial No. 58,510

Term of patent 7 years

To all whom it may concern:

Be it known that I, Albert Weewetzer, a citizen of the United States, residing at Elgin, in the county of Kane and State of Illinois, have invented a new, original, and ornamental Design for a Cosmetic Container, of which the following is a specification, reference being had to the accompanying drawing, forming part thereof, in which—

Fig. 2 is a side elevation of a cosmetic container showing my new design.

I claim:

The ornamental design for a cosmetic container, as shown.

ALBERT WEWETZER.
